UNITED STATES PATENT OFFICE

123,688

DESIGN FOR A PRESS OR THE LIKE

Louis A. Camerota, Burlington, N. J., assignor to
Florence Pipe Foundry & Machine Company,
Florence, N. J., a corporation of New Jersey

Application September 12, 1940, Serial No. 94,988

Term of patent 7 years

To all whom it may concern:

Be it known that I, Louis A. Camerota, a citizen of the United States, residing at Burlington, in the county of Burlington and State of New Jersey, have invented a new, original, and ornamental Design for Presses or the like, of which the following is a specification, reference being had to the accompanying drawing forming part thereof.

In the drawing, Figs. 1 and 2 are tilted or perspective views of a press or the like embody-

ing the ornamental design, the views being substantially from opposite sides of the press; Figs. 3 and 4 are elevations of the press, from the front and from the left in Fig. 1; and Fig. 5 is a plan view of the press.

In Figs. 1, 2, and 3, the movable press head is shown in an elevated or raised position.

I claim:

The ornamental design for a press or the like, as shown and described.

LOUIS A. CAMEROTA,
